(57) **CLAIM**

The ornamental design for a customizable marketing apparatus, as shown and described.

DESCRIPTION

FIG. 1 is a front, facing view of an unfolded customizable marketing apparatus including our design;

FIG. 2 is a front, facing view of the unfolded customizable marketing apparatus with three tabs extending from the left most flap folded in according to our design;

FIG. 3 is a bottom profile view thereof;

FIG. 4 is a front, facing view thereof with the rightmost flap folded in;

FIG. 5 is a bottom profile view thereof;

FIG. 6 is a front, facing view thereof with the rightmost flaps folded in and the leftmost flap folded in;

FIG. 7 is a bottom profile view thereof;

FIG. 8 is a rear, facing view thereof with the two rightmost flaps folded in and the leftmost flap folded in;

FIG. 9 is a bottom profile view thereof;

FIG. 10 is a front, perspective view thereof with an open front flap; and,

FIG. 11 is a front, perspective view thereof with a closed front flap.

The heavyweight broken line showing of elements on the customizable marketing apparatus illustrate fold lines. The lighter weight broken line showing of elements on the customizable marketing apparatus illustrate portions of the article and form no part of the claimed design.

1 Claim, 6 Drawing Sheets
